UNITED STATES PATENT OFFICE.

OSCAR F. SHEPARD, OF CINCINNATI, OHIO, ASSIGNOR TO THE WARNER ELEVATOR MFG. COMPANY, OF CINCINNATI, OHIO, A CORPORATION OF OHIO.

ELEVATOR-GOVERNOR.

1,291,195.

Specification of Letters Patent.

Patented Jan. 14, 1919.

Application filed April 2, 1917. Serial No. 159,211.

To all whom it may concern:

Be it known that I, OSCAR F. SHEPARD, a citizen of the United States, and residing at Cincinnati, in the county of Hamilton 5 and State of Ohio, have invented a new and useful Improvement in Elevator-Governors, of which the following specification is a full disclosure.

My invention relates to an improved 10 safety device for elevators. One of the objects of the invention is to provide governor controlled means for operating a brake mechanism on the elevator, and also preferably that the governor mechanism when actuated by a danger speed of the elevator, 15 will also operate a switch to throw out the power, whereby the brake mechanism on the car, as well as the power cut-out, are automatically actuated by the influence of a 20 predetermined elevator speed.

Of course, this emergency provision is functional during the travel of the elevator, when through overweighting or breaking of primary controls, or for other unaccount- 25 able reasons, the control of the elevator speed is lost, at which time the speed acceleration beyond normal operates through the governor to shut off the power and to function the safety brake.

The invention is applied to the type of 30 elevator controlling mechanisms wherein an endless cable is arranged in the elevator shaft, weighted at its lower end and its upper end passing over a governor wheel, 35 the cable being attached at a suitable place to the elevator so that normally it travels in unison therewith. There is a brake mechanism on the under side of the car, operative in relation to the tracks or guide rails of 40 the shaft and actuated by a cable mechanism on the car, one end of which is attached to the governor cable, and the invention provides means whereby the braking or stopping of the governor cable, through excess 45 speed, automatically operates the elevator brake cable.

The features of the invention are more 50 fully set forth in the description of the accompanying drawings forming a part of this specification, wherein:

Figure 1 is an elevation of an elevator showing the herein described safety governor applied thereto.

Fig. 2 is a bottom plan view showing the elevator brake mechanism. 55

Fig. 3 is an enlarged detail section on line 3-3 of Fig. 1.

Fig. 4 is an enlarged detail section on line 4-4 of Fig. 3.

Fig. 5 is an enlarged front elevation of 60 the safety governor.

Fig. 6 is a section on line 6-6 of Fig. 7, showing the toggle broken and the lock arms in rope engaging position.

Fig. 7 is an enlarged side elevation of the 65 governor partly broken.

Fig. 8 is a detailed section on line 8-8 of Fig. 5.

For convenient illustration, I have shown the outline merely of a freight elevator, comprising the upright members 1, on each side of the shaft elevator floor 2, shaft rails 3, and elevator shoes 4 engaging the rails 3, the emergency brake comprising on each side of the elevator the pivoted bell crank levers 5 having at their outer ends brake shoes 6 positioned upon opposite sides of the rail 3, and arranged to clamp upon this rail under speeds which bring the governor into emergency function. The mechanism for operating the bell crank levers 5 will be later described. 70 75 80

At the upper end of the elevator shaft is a governor supporting bracket 7 having bearing posts 8, in which is journaled a shaft 9 carrying a governor sheave or wheel 10, having the grooved periphery for the cable 11. This is an endless cable in the suspended loop of which is a weight 12 having the sheave 13 riding in the loop end of the cable, 90 and preferably this weight is tracked or guided by having guide-ways 14 engaging a track or guide 15 extended in the shaft, appropriately supported in the shaft by means of a bracket 16, (see Fig. 2). The details of 95 the governor mechanism operated by this wheel 10 will be later described.

The bell crank levers 5 are operated by a cable 17 mounted on the bottom of the elevator and a clamping device 18 is provided, (see Figs. 3 and 4), for attaching both the governor cable 11 and the brake operating cable 17 to the elevator, by clamping bolts 19, the clamp 18 being carried by the traveling cable 11, the lower end of 105 this clamp 18, and the cables 11, 17, passing

through the collar 20, fixed to the elevator. The lower end of the clamp member 18 has a detent 21, and the collar 20 has a sleeve 22 in which is a spring actuated latch 23 for 5 engaging and disengaging the detent. When the elevator is ascending, the collar 20 will engage under the head portion of the member 18, which is of a width sufficient to extend over the said collar thereby causing the 10 elevator to travel in unison with the cable 11, the brake operating cable 17 being normally stationary relative to the elevator; and when the elevator descends under normal conditions, the detent and latch will 15 hold the cable 11 and the elevator in unison travel, while under abnormal conditions of descent, where danger speed is attained, the automatic mechanism stops the cable 11 and holds it rigidly against motion so that the 20 elevator weight will release the latch 23 from detent 21, and the upper end of the brake cable 17, being held stationary by its attachment to the cable 11 through the clamp member 18, will draw the cable 17 25 into motion actuating the bell crank levers 5 as follows:

The cable 17, from the clamp piece 18, passes downwardly to the floor of the elevator, around the sheave 24 on the car, 30 thence passing under the car over sheave 25 to a drum 27 on shaft 28 extending transversely on the under side of the car and mounted in suitable bearings 29, the opposite ends of the shaft having the right and left 35 screw threaded portions 30, which engage into the wedge blocks 31, carrying antifrictional rollers 32. These bell crank levers 5 are pivoted at 33, their inner ends 34 lying upon opposite sides of the wedge blocks and 40 providing the camming surfaces 35 which are engaged by the rollers of the wedge blocks to move the arms inwardly or outwardly to clamp the brake shoes 6 upon the rails 3 when the governor cable 11 is locked 45 against motion.

This elevator emergency brake mechanism actuated by the cable 17 is of standard construction, which, unitarily considered, may be regarded as an elemental exponent of the 50 combination constituting my invention.

Returning now to the governor mechanism, (Figs. 5, 6, 7 and 8), which is automatically operated by predetermined speed to lock the cable 11, an elongated bearing 36 55 is formed for the extended governor wheel shaft 9, on the inner end of which is the beveled gear 37 meshing with the beveled gear 38, fixed to the governor shaft 39, on the upper end of which is suspended the conventional weighted governor arms 40, carrying 60 the suspended governor sleeve 41 rotatively on the shaft 39, there being a plurality of lugs or actuating members 42 at the lower end of the sleeves 41, which first 65 actuate the power switch and subsequently

break the toggle joint of the cable brake after the switch is thrown. These lugs have cam upper surfaces to produce a more positive lifting action against the toggle joint during the rotation of the governor sleeve. 70 The switch mechanism 44 is operated by a switch throwing arm 45 having a pin 46 projected in the orbit of rotation of the operating lugs 42 on the sleeve 41; when the speed of the governor raises the sleeve to a 75 predetermined point, the lug, first striking the pin 46, will throw the switch arm and actuate the switch to shut off the power through appropriate electrical connections, the detail of which need not be described. 80

In addition to this automatic power cut-out, and in order to mechanically and positively lock the cable 11 against motion, I provide the following instrumentalities which coact with the governor wheel 10 and the cable 11. On opposite sides of the governor wheel are pivoted the upright lock arms 47, the upper ends of which are connected by toggle links 48-49, the central connecting pin of which has an anvil member 50 projected laterally directly in the orbit of rotation of the cam lugs 42, of the governor sleeve, and positioned at a slightly higher location than that of the switch operating lever pin 46. Through the extremities 95 of these arms 47 passes the rod 52 carrying heavy coil springs 53 externally and which normally and forcibly press the arms toward one another when the joint of the toggle member is aligned, and when the toggle is 100 broken upwardly by the lugs 42, the arms are thrown forcibly together as shown in Fig. 6, for clamping the cable 11, and locking the wheel 10.

It will be understood that this constitutes 105 a safety mechanism and the toggle joint its member to be tripped by a governor member. The governor member has a fixed radius and is movable in alignment with the toggle joint to be broken.

The specific brake and lock mechanism comprises a series of lugs 54 on the lateral margins of the wheel 10, the arms 47 having the lateral lugs 55 for interlocking the lugs 54; that is, when the toggle is broken, the 115 lugs 55 are interposed into the orbit of rotation of the lugs 54. As shown in Fig. 7, the arms 47 are preferably of bifurcated formation and adjacent lugs 55 are cross-webbed by a cable shoe 56, positioned coincidently 120 adjacent to the cable-way 57 of the wheel 10, in position to extend into the cable groove and engage the cable 11 when the toggle joint is broken and the arms 47 are sprung inwardly.

The operation, briefly, is that at the predetermined danger speed the governor sleeve is raised to first operate the switch and then to break the toggle joint so that the brake projections 56 will first frictionally engage 130

the cable 11 with great force checking the rotation of the wheel and then the lugs 54 and 55 will interlock to positively hold the wheel and cable against rotation. The car 5 will then automatically detach from the cable clamp member 18, unwinding the brake cable 17 from its drum to automatically 10 actuate the brakes 6, which clamp upon the rail 3 of the elevator shaft and so arrest the motion of the car in the shaft and hold it 15 stationary.

The tripping of the toggle, or breaking the joint is effected by the driving or hammering action of the cam lugs 42 against the 15 toggle joint anvil member 50, and so has the full driving force incident to the momentum of the governor rotation, and hits the toggle joint roller forceful blows in an upward direction. In other words, the toggle trip 20 is operated by a blow or series of blows, and the vertical movement of the sleeve places the hammer lug in position for breaking the toggle joint.

Having described my invention, I claim:

1. In a device of the class described, a 25 governor, a cable and cable wheel, a safety, cable-gripping mechanism having a member to be tripped adjacent the governor, said member holding the safety mechanism under 30 tension normally inoperative in relation to the said cable and wheel, a governor operated hammer member having a fixed radius and movable at a predetermined speed to operatively contact the member to be 35 tripped.

2. In a device of the class described, a cable and cable wheel, a spring operated clutching mechanism therefor, and a member to be tripped holding said clutching 40 mechanism normally inoperative, a centrifugal governor mechanism, and a governor operated member having a fixed radius and movable with variations of governor speeds in alinement with the member to be tripped.

45 3. In a device of the class described, an elevator cable wheel and cable, a centrifugal governor operated by the wheel, a cable-gripping mechanism, a member to be tripped holding the gripping mechanism under tension and normally inoperative, a governor 50 operated rotary hammer sleeve in alinement with the member to be tripped, and adapted to hit the member to be tripped at a predetermined speed to release the tension and operate the gripping mechanism.

55 4. In a device of the class described, an elevator cable and cable wheel, a centrifugal governor operated thereby, a safety mechanism having a member to be tripped, said 60 mechanism and member being normally disconnected from the cable, wheel and governor, said member being positioned radially in the wheel plane, a governor operated rotary member movable in a plane parallel 65 with and radially relative to the wheel,

formed with a tripping member alined with the member to be tripped and adapted to operatively contact therewith at a predetermined governor speed.

5. In combination with a governor cable, 70 an elevator brake mechanism, an actuating cable therefor connected to the governor cable, a cable governor wheel having a lock member, a governor operated by the speed of the cable and wheel, a stop mechanism 75 comprising a member to brake the cable on the wheel, and a member to interlock with the wheel, a toggle normally holding the brake and interlock out of engagement with the wheel, said toggle being disengaged 80 from the governor mechanism at normal speeds, and a member on the governor adapted to release the toggle at a predetermined speed to clamp the cable and stop the wheel, and an electric switch adapted to be 85 operated by the governor in advance of the actuation of the stop mechanism.

6. In combination with a governor cable, an elevator brake mechanism, an actuating cable therefor connected to the governor 90 cable, a cable governor wheel having a lock member, a governor operated by the speed of the cable and wheel, a stop mechanism comprising a member to brake the cable on the wheel, and a member to interlock with 95 the wheel, a toggle normally holding the brake and interlock out of engagement with the wheel, said toggle being disengaged from the governor mechanism at normal speeds, a member on the governor adapted to release 100 the toggle at a predetermined speed to clamp the cable and stop the wheel, and an electric switch adapted to be operated by the governor in advance of the actuation of the stop mechanism.

7. In combination with a governor cable, an elevator brake mechanism, an actuating cable therefor connected to the governor cable, a cable governor wheel having a lock member, a governor operated by the speed of 110 the cable and wheel, a longitudinally moving member operated by the governor and having a rotary hammer, a stop mechanism comprising a member to brake the cable on the wheel, and a member to interlock with 115 the wheel, and a tension toggle normally holding the brake and lock out of engagement with the wheel, said toggle being positioned in the path of movement of the rotary hammer whereby the toggle joint is automatically broken by the hammer at a predetermined speed.

8. In combination with a governor cable, an elevator brake mechanism, an actuating cable therefor connected to the governor 125 cable, a cable governor wheel having a lock member, a governor operated by the speed of the cable and wheel, a longitudinally moving member operated by the governor and having a rotary hammer, a stop mech- 130

anism comprising a member to brake the cable on the wheel, and a member to interlock with the wheel, a tension toggle normally holding the brake and lock out of engagement with the wheel, said toggle being positioned in the path of movement of the rotary hammer whereby the toggle joint is automatically broken by the hammer at a predetermined speed, and an electric switch 10 adapted to be operated by the governor in advance of the actuation of the stop mechanism.

9. In combination with a governor cable, an elevator brake mechanism, an actuating 15 cable therefor connected to the governor cable, a cable governor wheel having a lock member, a governor having a sleeve rotating therewith and longitudinally movable with the governor speed variation, said 20 sleeve having a hammer, a stop mechanism comprising arms pivotally supported upon opposite sides of the governor wheel and each having a member to brake the cable on the wheel, and a member to interlock 25 with the wheel, and a tension toggle member holding said arms normally free from the wheel, said toggle being disconnected from the governor with its joint positioned to be broken by the hammer at a predetermined 30 position of the governor sleeve.

10. In combination with a governor cable, an elevator brake mechanism, an actuating cable therefor connected to the governor cable, a cable governor wheel having a lock 35 member, a governor having a sleeve rotating therewith and longitudinally movable with the governor speed variation, said sleeve having a hammer, a stop mechanism comprising arms pivotally supported upon opposite 40 sides of the governor wheel and each having a member to brake the cable on the wheel, and a member to interlock with the wheel, a tension toggle member holding said arms normally free from the wheel, said toggle being disconnected from the governor with its joint positioned to be broken by the hammer at a predetermined position of the governor sleeve, and an electric switch 45 adapted to be operated by the hammer.

50 11. In combination with a governor cable, an elevator brake mechanism, an actuating cable therefor connected to the governor cable, a cable governor wheel, said wheel having a peripheral groove for the cable and 55 a peripheral lug to be interlocked, a governor having a sleeve rotating therewith and longitudinally movable with the speed variations, said member having a hammer, a stop mechanism comprising arms pivotally supported upon opposite 60 sides of the governor wheel, the ends of the arms being formed with a member to brake the cable on the wheel and to interlock with the wheel lug, and a tension toggle member holding said arms normally apart and away 65

from the wheel, said toggle being disconnected from the governor with its joint positioned to be broken by the hammer at a predetermined position of the governor sleeve.

12. In combination with a governor cable, 70 an elevator brake mechanism, an actuating cable therefor connected to the governor cable, a cable governor wheel, said wheel having a peripheral groove for the cable and a peripheral lug to be interlocked, a governor having a sleeve rotating therewith and longitudinally movable with the speed variations, said member having a hammer, a stop mechanism comprising arms pivotally supported upon opposite sides of the governor wheel, the ends of the arms being formed with a member to brake the cable on the wheel and to interlock with the wheel lug, a tension toggle member holding said arms normally apart and away from the wheel, 80 said toggle being disconnected from the governor with its joint positioned to be broken by the hammer at a predetermined position of the governor sleeve, and an electric switch adapted to be operated by the hammer in 85 advance of the actuation of the stop mechanism.

13. In combination with a governor cable, 90 an elevator brake mechanism, an actuating cable therefor connected to the governor cable, a cable governor wheel, a governor operated by the cable and wheel, a rotary hammer member driven by the governor and movable longitudinally with the speed variations, a stop mechanism for the wheel and cable normally disconnected from the wheel and governor, and means whereby said stop mechanism is operated by the rotary hammer at a predetermined governor speed. 95

14. In combination with a governor cable, 100 an elevator brake mechanism, an actuating cable therefor connected to the governor cable, a cable governor wheel, a governor operated by the cable and wheel, a rotary hammer member driven by the governor and movable longitudinally with the speed variations, a stop mechanism for the wheel and cable normally disconnected from the wheel and governor, means whereby said stop mechanism is operated by the rotary hammer at a predetermined governor speed, an 105 electric switch, and a governor operative member therefor.

15. In a device of the class described, a 110 shaft, pivoted arms and governor balls, a sleeve on the shaft rotatable therewith and connected to the arms for longitudinal motion, a cable wheel close to the governor and having its axis transverse to the governor shaft, transmission mechanism connecting the wheel and shaft, normally-restrained gripping mechanism for said wheel, a hammer member on said sleeve, said mechanism having a member to be tripped by the hammer. 115

16. An elevator wheel and shaft, a governor and its shaft, said shafts being gear-connected in transverse planes, a governor sleeve having a rotary hammer, a wheel 5 gripping mechanism, an anvil member holding said mechanism normally inoperative and positioned in the axial line of movement of the rotary hammer.

17. An elevator wheel and shaft, a governor and its shaft, said shafts being gear-connected in transverse planes, a governor sleeve having a hammer movable axially with speed variations, a gripping mechanism spring-pressed toward the wheel, and a toggle joint member having an anvil portion 15 alined with the hammer, said member holding the gripping mechanism normally inoperative.

18. In a device of the class described, an elevator transmission operated governor, an electric switch having a member to be tripped and a transmission mechanical control having a member to be tripped, said members to be tripped being positioned in 25 relation to the governor to operate the switch in advance of the mechanical control, and a member rotatable with the governor and adapted to be successively brought into operative relations with the members to be tripped at predetermined speeds, said governor member being formed with a hammer 30

adapted to operatively strike the members to be tripped in said sequence at predetermined governor speeds.

19. An elevator wheel, gripping mechanism normally inoperative in relation to said wheel, a toggle for holding and releasing said mechanism having an anvil joint, a governor sleeve, and a rotary hammer on the sleeve having a fixed radius and movable 35 axially to strike the anvil and break the toggle joint.

20. In a device of the class described in combination with a rotary member to be stopped, a shaft, pivotal arms and governor 40 balls, a sleeve on the shaft rotating therewith and connected to the arms for longitudinal motion, a hammer on the sleeve, and a toggle controlled gripping mechanism normally inoperative in relation to said 45 rotary member and positioned to be struck by the hammer to break the joint and operate the grip at a predetermined governor speed.

In witness whereof, I hereunto subscribe 50 my name, as attested by the two subscribing witnesses.

OSCAR F. SHEPARD.
